UNITED STATES PATENT OFFICE.

CHARLES A. MABIE, TRUMAN H. WHITCOMB, AND JOHN T. BROWN, OF ALBION,
NEW YORK.

IMPROVEMENT IN STEAM-HEATERS FOR RAILROAD CARS.

Specification forming part of Letters Patent No. 122,326, dated January 2, 1872.

SPECIFICATION.

We, CHARLES A. MABIE, TRUMAN H. WHITCOMB, and JOHN T. BROWN, of Albion, in the county of Orleans and State of New York, have invented certain Improvements in Apparatus for Heating Cars by Steam, of which the following is a specification:

Nature and Objects of the Invention.

The first part of our invention relates to the combination of suitable radiating pipes and a main or feeding-pipe, in such a manner that the supply of steam to the radiating pipes may be regulated by means of a stop-cock, which is operated from the inside of the car by a lever working in front of a graduated dial. The second part of our invention relates to the combination, with the main pipe, of a coupling which shall be capable of being quickly coupled, and at the same time it is so constructed as to become uncoupled in case of an accidental separation of the cars. This coupling is provided with valves which close automatically on the separation of the coupling. It is also provided with a steam-trap, which allows the water to escape that might otherwise accumulate in the sag in the pipe between the cars.

Description of the Accompanying Drawing.

Figure 1 is a longitudinal elevation of a portion of a car. Fig. 2 is a plan of the pipes. Fig. 3 is a longitudinal vertical section of the coupling. Fig. 4 is a transverse section of the coupling taken on the line *x x* in Fig. 3. Fig. 5 is a side elevation of the coupling.

General Description.

A is a main or feeding-pipe extending from the locomotive-boiler through the entire train. *B B B*, &c., are radiating pipes, which are connected together at each end by the cross-pipes *C C'*. *D* is a stop-cock, which connects the pipe *A* with the cross-pipe *C'*. *E* is a rod, fixed to the plug of the stop-cock and extending to the side of the car, where it is provided with the lever *a*. *F* is a lever, placed in front of the dial *b* and connected with the lever *a* by the rod *c*. *G* is the coupling, which is provided with the straps *d d*, which swing on the

posts *e e*, placed in the part of the coupling designated by *P*. A forked lever, *f*, is connected with the straps *d d* by means of a joint at *g*. *h h* are posts in the part *H* over which the short ends of the forked lever hooks. *I* is a spring-catch, which is placed in such a position as to be capable of retaining the lever *f* when it is pressed down. *i* is a chain, connected with the top of the catch *I* at one end, while the other end is fastened to the car. *J J* are valves having the guides *j j*, and seats at *R R*; and the projecting stems *l l m m* are springs placed between the valves *J J* and the guides *j j*. *L* is a steam-trap, which surrounds the coupling and permits of the escape of water which may accumulate in the sag in the pipe through the aperture *n*. The coupling *G* is placed midway between the cars in the main pipe, which for a short distance each side of the coupling is made of some elastic material, or is jointed so as to allow the cars to separate and come together within certain limits.

When the coupling is made fast, (which is done by hooking the lever *f* over the post *h h* and bringing the long end of it under the catch *I*,) the stems of the valves *J J* meet and force them off their seats, making a free passage through the entire length of the main pipe. On a separation of the cars, the chain *i* being a little shorter than the elastic pipe, sufficient force is exerted on the catch *I* to release the lever *f* and uncouple the pipe. As the coupling is separated the valves *J J* are allowed to come down to their seats, preventing the escape of steam.

b is a dial, which is graduated and marked for heat and cold.

Claims.

We claim as our invention—

1. The combination of pipes *B B B*, &c., with the stop-cock *D*, rod *E*, lever *a*, lever *F*, and dial *b*, substantially as and for the purpose hereinbefore set forth.
2. The combination of the parts *P* and *H* with the straps *d d*, lever *f*, catch *I*, and chain *i*, substantially as and for the purpose hereinbefore set forth.
3. The combination of the steam-trap *L* with

the coupling G, substantially as and for the purpose hereinbefore set forth.

4. The combination of the valves J J with the parts P and H of the coupling G, substantially as and for the purpose hereinbefore set forth.

5. The feeding-pipe A, in combination with the above devices, when used to convey steam from the locomotive-boiler through a part or

the whole of a train, substantially as and for the purpose hereinbefore set forth.

Signed by us this 27th day of October, 1871.

CHARLES A. MABIE.

TRUMAN H. WHITCOMB.

JOHN T. BROWN.
